UNITED STATES PATENT OFFICE.

AUGUST L. PALIS, OF UPLAND, CALIFORNIA.

WATCH-HOLDER.

1,315,326.

Specification of Letters Patent. Patented Sept. 9, 1919.

Application filed October 31, 1918. Serial No. 260,522.

To all whom it may concern:

Be it known that I, AUGUST L. PALIS, citizen of the United States, residing at Upland, in the county of San Bernardino 5 and State of California, have invented certain new and useful Improvements in Watch-Holders, of which the following is a specification.

This invention relates to an improved 10 watch holder and has as its primary object to provide a device of this character adapted to support a watch upon an automobile wind shield in position where the watch may be easily seen by persons riding in the rear seat 15 of the vehicle as well as in the front seat thereof.

The invention has as a further object to provide a holder so constructed that when engaged over the upper edge of the lower 20 glass of a wind shield, said holder will be adapted to support a watch in inclined position tilted toward the shield so that the dial of the watch will be easily readable.

A further object of the invention is to 25 provide a holder having a resilient finger adapted to contact with the glass of the wind shield for supporting the body of the holder inclined with respect thereto and wherein the said tongue will thus be adapted 30 to prevent vibration of the holder against the glass and eliminate severe jolting of the watch when the vehicle is passing over rough roadways.

And the invention has as a still further 35 object to provide a holder which may also be employed as a stand for the watch, wherein in the stand may be arranged either in a vertical or rearwardly inclined position and wherein, when the stand is disposed in an 40 inclined position, the resilient finger of the holder will provide a prop therefor.

Other and incidental objects will appear during the course of the detailed description of the invention. In the drawings, wherein 45 I have illustrated the preferred embodiment of the invention, and wherein similar reference characters designate corresponding parts throughout the several views:

Figure 1 is a perspective view showing the 50 manner in which my improved holder is engaged with an automobile wind shield of conventional type, an ordinary watch being shown in position upon the holder.

Fig. 2 is a side elevation of the device 55 with the wind shield shown in section, this view particularly showing the manner in

which the spring finger of the device is adapted to yieldably hold the body of the holder away from the glass of the wind shield,

60

Fig. 3 is a side elevation showing the holder employed as a stand for the watch when the spring finger of the device becomes a prop for the stand,

Fig. 4 is a view similar to Fig. 3 and 65 illustrating the stand arranged in vertical position, and

Fig. 5 is a detail perspective view of the device.

In carrying the invention into effect, my 70 improved holder is preferably formed from a single piece of suitable resilient sheet metal cut to provide a somewhat elongated body 10 at the lower end of which are integrally formed legs 11 at opposite side edges of the 75 body. Extending from the side edges of the body adjacent its upper end is a pair of oppositely disposed clamping arms 12 which are inclined upwardly and are also longitudinally curved to resiliently engage around the 80 curved peripheral edge of a watch. At the lower end of the body 10 is formed a similar clamping arm 13 disposed between the legs 11, this latter clamping arm being adapted to engage around the peripheral edge of the 85 watch at its lower side to coact with the arms 12 for firmly clamping the watch upon the holder. At their outer ends, the arms 12 and 13 are preferably formed with rebent portions defining terminal loops 14 so that 90 the arms will present rounded edges at their terminals. Struck from the body medially thereof is a rearwardly inclined spring finger 15.

At its upper end, the body 10 is extended 95 to form a reduced neck 16 which carries a rearwardly directed and downwardly presented hook 17. As particularly brought out in Figs. 3, 4 and 5 of the drawings, the hook 17 is substantially channel shaped in cross 100 section and the bill portion 18 thereof is gradually flared or widened toward its free end to accordingly provide an increased bearing area therefor. Furthermore, as also brought out in these figures of the drawings, 105 the neck 16 is transversely bent at a point adjacent its lower end to thus support the hook as a whole in forwardly inclined position with respect to the body 10. Struck from the shank portion of the hook 17 at the 110 upper end of the neck 16 is a forwardly inclined lug or stud 19 and struck from the bill

portion of the hook medially thereof, is an inwardly and upwardly curved spring finger 20. In the drawings, I have shown a conventional watch 21 in position upon the holder. As there illustrated, the watch is seated against the body 10 and engaged at its periphery by the clamping arms 12 and 13 to be firmly held thereby upon the body, and the ring upon the watch stem is engaged over the stud 19 which will thus prevent rotation of the watch within the clamping arms upon the body. The watch will thus always be maintained in an upright position. Furthermore, as will be clear, the watch may be readily detached from the holder whenever desired.

Referring now to Fig. 1, I have shown the holder upon a conventional type of automobile wind shield 22 having an upper glass 23 and a lower glass 24. The hook 17 of the holder is, as shown in this figure, engaged over the upper edge of the lower glass preferably at a point substantially midway between the ends thereof. The tongue 20 will thus yieldably bear against the outer face of the glass for firmly connecting the holder therewith and, owing to the forward inclination of the hook 17 with respect to the body 10 of the holder, the hook will support the body 10 inclining downwardly away from the wind shield while the tongue 15 will rest against the inner face of the lower glass. This tongue will, therefore, sustain the body 10 with respect to the lower glass so that the watch will always occupy an inclined position with respect to the wind shield so that the dial of the watch will be easily readable. Furthermore, the watch may be seen by persons riding in the rear seat of the vehicle as well as by persons riding in the forward seat. The tongue 20 will, of course, maintain the shank portion of the hook 17 clamped against the front face of the lower glass of the wind shield and will thus act, as particularly brought out in Fig. 2, upon the body 10 of the holder to maintain the finger 15 slightly compressed between the body and said glass. The tongue and finger will thus yieldably coat with the glass to prevent vibration of the holder with respect to the glass. Furthermore, by this construction, the finger 15 will act to prevent severe jolting of the watch when the vehicle is passing over rough roadways.

In Fig. 3, I have shown the holder in use as a stand for the watch. As illustrated in this figure, the legs 11 of the holder may be rested upon a suitable support and the holder tilted rearwardly to engage the tongue 15 with the support, when the tongue will provide a prop for the holder for sustaining the watch in rearwardly inclined position. When so used the holder will provide a very attractive desk or table stand for the watch. In some instance it may be de-

sired to have the watch supported in a vertical position, and in Fig. 4 I have shown the holder disposed to support the watch in such position. As illustrated in this figure, the body 10 of the holder is tilted forwardly 70 until the spring arm 14 engages with the support sustaining the holder when said arm will form a leg coacting with the legs 11 for maintaining the holder in an upright position. I accordingly provide a very simple construction for the purpose set forth and a device which may, when a person is riding in an automobile, be readily attached to the wind shield thereof while, when desired, the holder may be detached and used 80 as a watch stand.

Having thus described the invention, what is claimed as new is:

1. A device of the character described including a body, means carried thereby for connecting a timepiece with the body, suspending means carried by the body, and yieldable means extending from the body and adapted to bear between the body and an object engaged by said suspending means 90 for yieldably supporting the body with respect to said object.

2. A device of the character described including a body, means carried by the body for connecting a timepiece therewith, suspending means for the body, and yieldable means respectively carried by said suspending means and the body and adapted to contact with an object engaged by said suspending means for yieldably clamping the body 100 upon and sustaining the body with respect to said object.

3. A device of the character described including a body, means carried by the body for connecting a timepiece therewith, suspending means for the body, and yieldable means carried by the body and adapted to bear between the body and an object engaged by said suspending means for yieldably sustaining the body with respect to 110 said object, said yieldable means being directed rearwardly from the body and adapted to provide a prop for supporting the body in rearwardly inclined position forming a stand.

4. A device of the character described including a body, means carried thereby for connecting a timepiece with the body, a suspending hook carried by the body, and a resilient tongue projecting within said hook 120 and adapted to bear against an object engaged by the hook for clamping the body upon said object.

5. A device of the character described including a body, means carried thereby for connecting a time piece with the body, a suspending hook for the body, a resilient finger directly rearwardly away from the body, and a resilient tongue carried by said hook and adapted to bear against an object en- 130

gaged by the hook for clamping the body upon said object compressing said finger between the body and the object whereby the finger will cushion the body with respect to 5 the object.

6. A device of the character described including a body, means carried thereby for connecting a time piece with the body, legs carried by the body, suspension means for 10 the body, and means carried by the body and adapted to bear between the body and an object engaged by said suspension means for yieldably sustaining the body with respect to said object, said last mentioned 15 means being adapted to provide a prop for supporting the body in rearwardly inclined position resting upon the legs and forming a stand.

7. A device of the character described including a body, a suspension hook therefor, means for connecting a time piece with the body, and a stud formed from the shank of said hook and adapted to engage through the ring of a time piece for holding the time piece against rotation upon the body. 20

8. A device of the character described including a body, supporting legs therefor, and means carried by the body for connecting a time piece therewith, said means being adapted to engage a surface coacting with 30 said legs for sustaining the body in upright position with respect to said surface providing a stand.

In testimony whereof I affix my signature.

AUGUST L. PALIS. [L.S.]
